ABSTRACT: A portable holder for soap which can be held by hand with a cake of soap detachably secured thereto for use in washing, bathing and the like, especially for bathing children and invalids.

Patented Nov. 24, 1970

3,542,411

INVENTOR.
JOSEPH J. FILAS

SOAP HOLDER

SUMMARY OF THE INVENTION

My holder includes a hollow body having the shape of a rectangular parallelepiped. A plurality of suction cups extend transversely outward from one surface of the body and lie in a common plane. These cups are detachably securable to a cake of soap whereby the holder with attached cake, due to the buoyancy of the holder will float in water whereby it can be easily recovered.

BRIEF DESCRIPTION OF THE DRAWINGS

In the drawings:

- FIG. 1 is a perspective view of my holder in use;
- FIG. 2 is a top view thereof;
- FIG. 3 is an end view thereof;
- FIG. 4 is a view through 4-4 in FIG. 2;
- FIG. 5 is a cross section of the end view of FIG. 3; and
- FIG. 6 is a bottom view of my holder perse.

DETAILED DESCRIPTION OF PREFERRED EMBODIMENTS

Referring now to FIGS. 1-6, there is shown a hollow body 10 having the shape of a rectangular parallelepiped, with roughened outer surfaces. All outer surfaces other than bottom surface 12 are provided with various finger receiving recesses 14 and 16. The rough surface enhances gripping in a nonslip manner and the recesses provide supports for fingers.

25
30

A plurality of suction cups 18, arranged in rows and columns and lying in a common plane, extend transversely outward from surface 12.

5 A cake of soap 20 can be detachably secured by these cups as shown.

A cruciform shaped brace or support 22 can be disposed within the body to provide additional rigidity and, at the same time, to divide the body into four like hollow chambers or compartments 24.

10 I claim:

1. A new portable holder or support for a cake of soap, said holder comprising:
a rectangular parallelepiped shaped body;
a plurality of suction cups adapted to detachably secure said cake to said body, said cups extending transversely to a selected surface of the body and lying in a common plane; said body defining a hollow sealed cavity of volume sufficient to displace a weight of water greater than the combined weight of said body, said suction cups, and said cake of soap reduced by the weight of water displaced by said cake of soap;
a cruciform shaped brace disposed in said body cavity and dividing same into four like hollow chambers, said brace adding rigidity to said body; and
the exposed surfaces of said body other than that supporting said cups are rough to prevent slippage when the holder is held by the hand and are provided with indentations which can be grasped by fingers.
